UNITED STATES PATENT OFFICE

2,027,183

REFRIGERATOR

Carl E. L. Lipman, Chicago, Ill., assignor to Lipman Patents Corporation, Chicago, Ill., a corporation of Delaware

Application July 30, 1932, Serial No. 626,300

3 Claims. (Cl. 62—116)

This invention relates to refrigerators and has for its purpose the provision of an improved refrigerator.

In accordance with my invention, I provide a refrigerator cabinet having a plurality of independent compartments which may be refrigerated to widely differing degrees of temperature to suit special purposes. Preferably the independent compartments are insulated from each other and are refrigerated by independent cooling elements supplied with refrigerant from a suitable source. It is also within the contemplation of my invention to disperse the cooling air circulated over the refrigerating unit in such a manner as not to disfigure the walls adjacent the refrigerator. Other novel features and their advantages will be apparent to those skilled in the art from the following description of one embodiment of my invention given in connection with the drawings in which:

Fig. 1 is a front elevation of a refrigerator constructed in accordance with this invention, a portion of one exterior door being broken away to illustrate the inner sealing door.

Fig. 2 is a vertical section taken on line 2—2 of Fig. 1, and

Fig. 3 is a horizontal section taken on line 3—3 of Fig. 2.

The illustrated refrigerator comprises a cabinet 1 having a relatively large storage compartment 2 and a smaller independent freezing compartment 3 formed by an insulated L-shaped partition 4 built integrally within the cabinet with the front wall set back from the front of the cabinet to provide an air space between the freezing compartment and the storage compartment formed by the partition wall. The front wall of the partition is provided with doorways sealed by inner doors 6 through which access may be had to the freezing compartment. Access may be had to the storage compartment through either of two exterior doors 7 or 8.

Within each of the compartments is a cooling element comprising in the present instance an evaporator 9 of the flooded type suspended in the freezing compartment 3 and a second evaporator 10 suspended in the storage compartment 2. In the illustrated embodiment of this invention the evaporator 10 is also of the flooded type and has an unusually large amount of effective surface in order to take advantage of the greatly increased capacity of a compressor when operated at a high back pressure. Either evaporator may, of course, be of any suitable type employing either natural or forced air circulation.

The two evaporators may be supplied with refrigerant from any suitable source. In the present instance a separate refrigerating unit including a sealed motor compressor 11, fan 12, condenser 13 and thermostatic control 14 and control switch 14^a is used to circulate refrigerant through each of the evaporators. The use of two units provides a very simple and efficient supply and control for each evaporator and therefore each compartment independently of the other evaporator and corresponding compartment. The refrigerating units are shown mounted upon the top of the cabinet, each unit being enclosed by a hood or casing 15 provided at its front with a grill 16 through which air may be taken in and further provided at its top with a series of louvers 17 through which the air is exhausted. As can be seen from Fig. 2 the louvers are arranged to direct the exhaust or discharge upwardly and forwardly thus dispersing the discharged air in such a direction as not to mar the walls or ceiling adjacent the refrigerator.

From the foregoing description it will be apparent that there is provided a refrigerator having a plurality of independent insulated refrigerated compartments one within the other and each cooled by its own cooling element, controlled by its own thermostat, set for its own desired temperature independent of the other. The compartments include an inner freezing compartment 30 which is independent of and insulated from the main storage compartment and by the storage compartment from the atmosphere and which may be refrigerated independently of the main storage compartment, the independent freezing 35 compartment being formed by an integral insulated partition wall. Due to the fact that the freezing compartment front wall and doors are set back from the front exterior wall of the cabinet, the temperature differential between the inside and outside of the freezing compartment is less than if the freezing compartment door were the exterior door. Similarly the temperature differential between the storage compartment and the exterior is less than if the storage compartment were open to or in communication with the freezing compartment and therefore operating at a lower temperature than necessary. The temperature differential being lessened, the heat transfer, particularly through the door openings, 40 is lessened and the efficiency of the entire box is raised.

The freezing compartment which need only be relatively small as it is normally utilized only for making ice or ice cream and storing frozen des- 50 55

serts and the like may be maintained at temperatures below freezing by a correspondingly small refrigerating unit most efficient for this purpose. The main storage compartment may be maintained at a temperature above freezing but sufficiently low for food preservation by a suitable unit independent of the freezing compartment unit. The storage compartment evaporator being separate and independently operated, may have a 10 large effective surface and need not be maintained at a temperature below freezing. Frosting, with its accompanying dehydrating action, in the main storage compartment and the necessity of defrosting can be eliminated by an evaporator of 15 this type. The foregoing arrangement permits maintaining the freezing compartment and/or the storage compartment at any desired temperature absolutely without affecting the other compartment since each is operated by its own thermostat which is unaffected by the temperature conditions of the other compartment. This is 20 not possible with prior boxes where one thermostat controlled one cooling element refrigerating both compartments.

25 In such installations the temperature of the storage compartment would affect the thermostat to the extent of causing it to shut off the refrigerant supply before the freezing compartment was cold enough, or if set to permit sufficient cooling of the freezing compartment would allow the temperature in the storage compartment to drop below freezing. In other words, there was no 30 independence of compartments and control as is obtained by my invention.

35 Other advantages will be apparent to those skilled in the art to whom it will also be apparent that minor changes may be made in the details of construction and arrangement without depart-

ing from the spirit and scope of the invention as defined in the appended claims.

I claim:

1. A refrigerator comprising a cabinet having a plurality of independent insulated compartments 5 therein having independent doors thereto, one compartment being within the other and having its door within the outer compartment, a cooling element in each of said compartments, an individual control for each of said elements, and 10 means for circulating refrigerant through each of said elements independently of the other elements.

2. A refrigerator comprising a cabinet having a plurality of independent insulated compartments 15 therein having independent doors thereto, one compartment being within the other and having its door within the outer compartment, a cooling element in each of said compartments, and individual control for each of said elements, and 20 a refrigerating unit for each of said cooling elements and arranged to circulate refrigerant therethrough independently of the other units and cooling units.

3. A refrigerator comprising a cabinet provided 25 with a freezing compartment and a storage compartment, said compartments being separated by an insulated partition built integrally into the cabinet, the front wall of said partition being set 30 back from the front wall of the cabinet, said freezing compartment having an inner door, an independent cooling element in each of said compartments, an individual control for each of said elements, and means for circulating refrigerant through each of said cooling elements independently of the other elements.

CARL E. L. LIPMAN.
